UNITED STATES PATENT OFFICE.

WILLIAM H. HART, JR., OF PHILADELPHIA, PENNSYLVANIA.

DESIGN FOR A BICYCLE-SUPPORT.

SPECIFICATION forming part of Design No. 30,818, dated May 16, 1899.

Application filed March 6, 1899. Serial No. 708,035. Term of patent 7 years.

To all whom it may concern:

Be it known that I, WILLIAM H. HART, Jr., a citizen of the United States, residing in the city and county of Philadelphia, State of Pennsylvania, have invented and produced a new and original Design for a Bicycle-Support, of which the following is a specification, reference being had to the accompanying drawings, forming part thereof.

The leading feature of my design for a bicycle-support is a leg of flaring form and a limb on the upper end thereof.

Figure 1 represents a perspective view of a bicycle-support embodying my design. Fig. 2 represents a vertical section thereof on line xx , Fig. 1.

In the drawings, A designates legs of the support, and B the base thereof. On the upper end of the legs are limbs C, which project angularly therefrom. The legs flare, as at D, from the upper portions to the base B.

Having thus described my invention, what I claim as new, and desire to secure by Letters Patent, is—

The design for a bicycle-support substantially as shown and described.

WILLIAM H. HART, JR.
